ATTORNEY.

UNITED STATES PATENT OFFICE.

GEORGE H. LELAND, OF DAYTON, OHIO, ASSIGNOR TO THE LELAND ELECTRIC COMPANY, OF DAYTON, OHIO, A CORPORATION OF OHIO.

SHORT-CIRCUITING DEVICE FOR MOTORS.

Application filed November 2, 1925. Serial No. 66,213.

This invention relates to short circuiting device for motors. Electric motors of the type known as repulsion induction motors are so constructed that they will start as repulsion motors and after they have attained a predetermined speed will be automatically converted into induction motors. This is usually accomplished by means of a series of weights or contact members arranged circumferentially of the axis of the commutator and movable by centrifugal force into short circuiting contact with the commutator bars, a yieldable member acting on the weights to resist their outward movement.

One object of the invention is to provide a short circuiting device of this character which will be simple in its construction, highly efficient in its operation and which may be produced at a relatively low cost.

A further object of the invention is to provide such a short circuiting device having means for so applying an annular contractile band to the weights that the band will cause the contact portions of the weight to press firmly against the face of the commutator at all times.

Other objects of the invention will appear as the device is described in detail.

In the accompanying drawings Fig. 1 is an end elevation, partly broken away, of a short circuiting device embodying my invention; Fig. 2 is a longitudinal sectional view taken centrally through such a short circuiting device and the commutator, showing the weights in their retracted positions; Fig. 3 is a similar view showing the weights in their extended positions; Fig. 4 is a sectional view showing a slightly modified form of my invention applied to a commutator; and Fig. 5 is a similar view showing a further modification of the invention.

In these drawings I have illustrated certain embodiments of the invention but it will be understood that these have been chosen for the purposes of illustration only and that the device may take various forms without departing from the spirit of the invention.

As here shown, the short circuiting device is applied to a commutator comprising a body portion 1 which is rigidly mounted on an armature shaft 2 and is provided with the usual circumferential series of commutator bars 3. Mounted on this shaft 2 and spaced some distance from the face of the commutator is a retaining plate or disk 4. This disk may be

loosely mounted on the shaft so that it is capable of both rotary and axial movement with relation thereto but its movement away from the face of the commutator is positively limited by a stop, such as a split ring 5 seated in a circumferential groove 6 in the shaft 2. Arranged between the disk 4 and the face of the commutator is an annular series of contact members or weights 7 which extend circumferentially of the shaft 2 and which are slidably mounted so that they may be moved outwardly by centrifugal force to cause the contact portions 8 at the outer ends thereof to be brought into short circuiting contact with the commutator bars 3, shown in Fig. 3. These weights may be of any suitable character and shape. Preferably they are tapered toward the axis of the shaft so as to provide flat surfaces between adjacent weights. A yieldable device is applied to the weights to resist their outward movement and the weights are preferably so constructed that this yieldable device will not only resist the outward movement thereof but will also cause the contact portions 8 thereof to be pressed firmly against the face of the commutator.

The yieldable device may be of any suitable character but I prefer that it should be in the form of a contractile band because the elasticity of such a band prevents any material sliding movement of the same relatively to the weights and thereby minimizes the friction. As here shown, this contractile band is in the form of an endless helical spring 9. Each of the weights 7 has a portion of its forward edge, that is the edge opposite the commutator, arranged to engage and fulcrum on the retaining disk 4 and, as here shown, the inner portions of the forward edges of the weights extend outwardly and rearwardly so as to provide slidable fulcrum points near the inner ends of the weights. The outer portions of these forward edges of the weights extend forwardly beyond the fulcrum point to form shoulders 10 which overhang the peripheral edge of the disk 4 and constitute stops to limit the inward movement of the weights. The contractile band is so applied to the weights that it will press the fulcrum points thereof against the disk 4 and will act on the weights, about their fulcrum points, to press the contact points 8 thereof against the face of the commutator.

To this end the contractile band is preferably connected with the weights between their respective centers of gravity 11.

and the commutator. With such an arrangement of the band the tendency of the same is to cause each weight to pivot about its point of contact with the disk and thus hold the outer contact portion thereof against the face of the commutator. There are various ways in which the contractile band may be so connected with the weights and in that form of the device shown in Figs. 1, 2 and 3, each weight is provided at its inner end with an arm 11 which projects from the rear edge of the body of the weight toward the commutator. In order to accommodate this arm the body 1 of the commutator is recessed in its forward face, as shown at 12, and the arms 11 extend into this recess. Each of the arms is provided in its outer edge with a shallow recess 13 in which the annular band 9 is seated. The recesses are preferably formed near the rear ends of the arms so as to provide a relatively long leverage through which the band will act on the contact portions of the weights.

In that form of the device shown in Fig. 4 the weights 14 are of the same general shape as the weights 7 and they pivotally contact with the disk 4 at 15 and are provided with shoulders 16 to limit the inward movement thereof, and with contact portions 17 to engage the commutator bars. These weights are provided in their inner portions and preferably near the inner ends thereof with openings 18 through which a contractile band 19 is threaded. Preferably the inner portions of the weights are widened so as to cause the annular band to engage the weights at a considerable distance in the rear of their centers of gravity and thus the band will tend to rotate the weights about their fulcrum points 15 and press the contact points 17 thereof against the face of the commutator. Obviously, if desired, the outer portions of the walls of the openings 18 may be cut away to facilitate the assembling of the weights and the spring.

In that form of the device illustrated in Fig. 5 the weights are shown at 20 and are similar in shape to the plates 14 of Fig. 4 but instead of having an opening through the same their inner rear corners are cut away to form a recess 21. A contractile band 22 is arranged in this recess and is suspended from the weights by suitable connecting devices, such as links 23, which are so arranged that the force of the band will be applied to the weights at points between the respective centers of gravity and the commutator.

In that form of the device shown in Figs. 1, 2 and 3, the forward ends of the commutator bars are flush with the face of the commutator and the contact portions of the weights move over the commutator bars with a sliding or wiping action. In those forms of the device shown in Figs. 4 and 5, the forward ends of the commutator bars overhang the face of the commutator and are

provided with arcuate recesses 24 which form the contact surfaces and which are engaged by the contact points of the weights. The contact points of the weights are curved to conform to the contour of the arcuate recesses 24, so that the weights will engage the commutator bars with a butting contact but the arrangement is such as to eliminate the burning or damaging of the contact faces due to sparking, as is fully set forth in my co-pending application filed April 16, 1925, Serial No. 23,524.

While I have shown and described certain embodiments of my invention I wish it to be understood that I do not desire to be limited to the details thereof as various modifications may occur to a person skilled in the art.

Having now fully described my invention, what I claim as new and desire to secure by Letters Patent, is:

1. In a short circuiting device for a commutator, a shaft on which said commutator is mounted, a disk mounted on said shaft, spaced from said commutator and normally held against axial movement in a direction away from said commutator, a series of short circuiting weights arranged about said shaft between said disk and said commutator and capable of radial sliding movement under the influence of centrifugal force, each weight having a portion of that edge opposite said commutator arranged to fulcrum at all times on said disk and having a portion of its other edge in sliding contact with the face of said commutator, and a contractile band acting on the several weights at points between their respective centers of gravity and said commutator to resist their outward movement and to press said portions thereof respectively against the face of said commutator and against said disk.

2. In a short circuiting device for a commutator, a shaft on which said commutator is mounted, a disk mounted on said shaft, spaced from said commutator and normally held against axial movement in a direction away from said commutator, a series of short circuiting weights arranged about said shaft between said disk and said commutator and capable of radial sliding movement under the influence of centrifugal force, each weight having a portion of that edge opposite said commutator arranged to fulcrum at all times on said disk and having a portion of its other edge in sliding contact with the face of said commutator, each weight also having a part extending toward said commutator, and a contractile band supported on the last mentioned parts of said weights.

3. In a short circuiting device, the combination with a shaft and a commutator mounted on said shaft, comprising a circumferential series of bars and having a central recess in the face thereof, of a disk mounted

on said shaft and spaced from the face of said commutator, an annular series of contact weights mounted between said disk and the face of said commutator and arranged circumferentially of said shaft for sliding movement under the influence of centrifugal force into short circuiting contact with said bars, each weight having a part arranged to fulcrum at all times on said disk and having another part extending into said recess in said commutator, and a contractile band supported by the last mentioned parts of said weights.

4. In a short circuiting device for a commutator, a shaft on which said commutator is mounted, a disk mounted on said shaft, spaced from said commutator and normally held against axial movement in a direction away from said commutator, a series of short circuiting weights arranged about said shaft between said disk and said commutator, capable of radial sliding movement under the influence of centrifugal force and each having a portion arranged to have short circuiting contact with said commutator, and a spring element acting on said weights at all times

to press the contact portions thereof against the commutator and to press other portions thereof against said disk.

5. In a short circuiting device for a commutator, a shaft on which said commutator is mounted, a disk movably mounted on said shaft and spaced from said commutator, means for limiting the movement of said disk in a direction away from said commutator, a series of short circuiting weights arranged about said shaft between said disk and said commutator and capable of radial sliding movement under the influence of centrifugal force, each weight having a contact portion adapted to have short circuiting contact with the commutator and another portion to engage said disk, and a spring element acting on said weights to press said contact portions thereof against said commutator and to press said other portions thereof against said disk and hold said disk against said means for limiting the movement thereof.

In testimony whereof, I affix my signature hereto.

GEORGE H. LELAND.

CERTIFICATE OF CORRECTION.

Patent No. 1,713,610.

Granted May 21, 1929, to

GEORGE H. LELAND.

It is hereby certified that the above numbered patent was erroneously issued to "The Leland Electric Company, of Dayton, Ohio, a corporation of Ohio", as assignee of the entire interest in said invention, whereas said patent should have been issued to the inventor, said "Leland, and The Leland Electric Company, of Dayton, Ohio, a corporation of Ohio", said corporation being assignee of one-half interest only in said invention, as shown by the records of assignments in this office; and that the said Letters Patent should be read with this correction there in that the same may conform to the record of the case in the Patent Office.

Signed and sealed this 18th day of June, A. D. 1929.

M. J. Moore,
Acting Commissioner of Patents.
